No. 778,979.

PATENTED JAN. 3, 1905.

A. F. LARSON.

ROLLER FOR PIANO PLAYING ATTACHMENTS.

APPLICATION FILED JAN. 24, 1903.

UNITED STATES PATENT OFFICE.

AXEL F. LARSON, OF CHICAGO, ILLINOIS

ROLLER FOR PIANO-PLAYING ATTACHMENTS.

SPECIFICATION forming part of Letters Patent No. 778,979, dated January 3, 1905.

Application filed January 24, 1903. Serial No. 140,859.

To all whom it may concern.

Be it known that I, AXEL F. LARSON, of Chicago, in the county of Cook and State of Illinois, have invented certain new and useful 5 Improvements in Rollers for Piano-Playing Attachments, of which the following is a specification.

The present invention relates to an adjustable roller for piano-playing attachments or 10 other musical instruments in which perforated sheets of paper are employed for actuating the instrument, the object being to provide means for readily adjusting the roller longitudinally and for mounting it. This and other 15 novel features of construction are illustrated in the accompanying drawings and will herein-after be fully described.

In the drawings, Figure 1 is a sectional elevation of a portion of a piano-playing attachment in which there is an adjustable roller embodying features of my invention, and Fig. 2 is a sectional detail taken on the line 22 of Fig. 1.

In illustrating my invention I have only 25 shown such parts as are immediately related to the roller. The device consists principally of a roller for winding or feeding the paper, bearings for the roller, and means for adjusting it longitudinally. These features are set 30 forth in the following description.

A refers as a whole to the framework of a piano-playing attachment or similar instrument.

B refers to a roller upon which perforated 35 musical sheets may be wound. This in itself may be of any well-known shape, and, as shown, consists of a central spindle b, provided at its ends with disks b', and situated on the ends axially are small recesses b² and b³, the recess b² being square or of key shape, so 40 that the roller may be turned when a small shaft is inserted therein, while the recess b³ is rounded, so as to permit the roller to turn freely on a stud inserted therein.

C is a plunger provided on its end next the 45 roller with a stud c, which is adapted to engage the recess b³ in roller and forms a trunnion for the roller. The plunger C is movable in a tubular casing c'. This casing is 50 held in a fixed position on framework of the

instrument by means of a flange c¹⁰ and a nut c⁵, which engages a screw-threaded part c' on said casing.

C' is a rod connected to the plunger C and projecting outwardly from the casing. On 55 the outer end of the rod C' is a button or handle c⁵. Inclosed within the casing c' is a coiled spring c⁴. This presses against the plunger and tends to keep same against the roller B.

D is a head provided at one end with a 60 short central shaft or stud d, which is adapted to engage the recess b³ on the end of the roller B. This stud is preferably square and revolves the roller when the head is actuated. The head D consists of an end part d', preferably tapered, as shown, at d', and is provided with a hollow spindle or sleeve d³, having a bore d³⁰. Mounted on this spindle is a rear part d⁴, held in place by a nut d⁵. Between the parts d' and d⁴ is a stationary collar d⁶. 70 This collar is mounted between the two parts on balls d⁷, which run in grooves d⁸. The collar d⁶ is provided with pins d⁹, and the hollow spindle d³ has fixed pins or cross-pieces d¹⁰. 75

E is a drive-shaft provided on its inner end with a slot e, so as to form a forked end e', which engages the pins d¹⁰ in the bore d³⁰ and thus revolves the movable parts of the head D. This drive-shaft may have bearings of 80 any suitable description in the framework of the instrument, and, as shown, these consist of a collar e², mounted in a flanged bushing e³, attached to the framework A. On the shaft E is mounted a collar e⁴ and a drive-wheel E', 85 secured in place by a nut e⁵. The parts e², e⁴, and E' have grooves e⁶ and ball-bearings e⁷.

F is a lever for moving the head D longitudinally. This lever is pivoted at f to a bracket f'. Its lower end is forked at f¹⁰ and engages 90 the pins d⁹ on the collar d⁶, so as to move the head. The upper part of the lever has a screw-threaded bore f², and f³ is a screw-threaded rod which passes through and engages the same, so as to oscillate or move the lever to a 95 certain extent on its pivot. The rod f³ is provided on its outer end with a turning disk or wheel f⁴, and at its inner it is pivoted and secured to the bracket f' at f⁵.

It will thus be seen from the foregoing that 100

my invention provides means by which a roller may be readily inserted or removed from the instrument and also quickly adjusted longitudinally into any desired position. The bearings described also provide durable and light-running devices for the purpose.

While I have shown my adjusting device for moving one roller longitudinally, it is apparent that the same may be modified to some extent without departing from the spirit of the invention and may be also applied to operating two rollers or to a series of rollers.

What I claim is—

- 15 1. In a device of the class described, the combination with a roller, of a spring-actuated plunger axially engaging the roller at one end, a driving-chuck frame engaging the other end of said roller, a collar on said chuck-frame having ball-bearing on said frame, a lever pivoted at an intermediary point, one end of said lever being bifurcated, the bifurcated ends being pivoted to said collar, an adjusting-screw engaging the other end of said lever by means of which said driving-chuck may be moved toward or away from said roller, and means for driving said chuck-frame.
- 20 2. In a device of the class described, the combination with two supporting-frames, of a roller disposed between said frames, a spring-actuated plunger mounted on one frame and axially engaging one end of said roller, a driving-chuck frame engaging the other end of

said roller, said chuck-frame consisting of a shoulder portion and a bearing portion, a collar d^4 engaging the bearing portion, a collar d^6 disposed between the shoulder portion and the collar d^4 and having ball-bearing with said shoulder and collar, an axial bore through said chuck-frame, a slotted shaft extending into said bore, pins extending through said bearing portion and the slot through said shaft, said shaft having a square end, a journal-box mounted on said other support, the square end of said shaft passing through said bearing - box adapted to turn therein, an 45 outer and inner ring secured to said shaft and having ball-bearing against the sides of said journal - box, a gear - wheel mounted on the outer collar for driving said shaft and the chuck engaged thereby, a lever pivoted at an intermediary point, said lever having a bifurcated end, the ends of which are pivoted to the collar d^6 , and an adjusting-screw engaging the other end of said lever and said other frame, whereby said chuck may be moved toward or away from said roller and longitudinally along said shaft.

Signed at Chicago this 22d day of December, 1902.

AXEL F. LARSON.
